(57) **CLAIM**

The ornamental design for a beverage dispenser, as shown and described.

DESCRIPTION

FIG. 1 is a front perspective view of the beverage dispenser of the present invention.

FIG. 2 is a rear perspective view of the beverage dispenser.

FIG. 3 is a front elevational view of the beverage dispenser.

FIG. 4 is a right elevational side view of the beverage dispenser, the left side view being omitted because it is a mirror image of FIG. 4;

FIG. 5 is a rear elevational view of the beverage dispenser.

FIG. 6 is a top plan view of the beverage dispenser; and, FIG. 7 is a bottom plan view of the beverage dispenser.
